UNITED STATES PATENT OFFICE

169,431

REFRIGERATOR CABINET

Montgomery Ferar, Royal Oak, Mich., assignor to
Seeger Refrigerator Company, St. Paul, Minn.,
a corporation of Minnesota

Application December 11, 1952, Serial No. 22,646

Term of patent 14 years

(Cl. D67—3)

To all whom it may concern:

Be it known that I, Montgomery Ferar, a citizen of the United States and resident of Royal Oak, in the county of Wayne and State of Michigan, have invented a new, original, and ornamental Design for a Refrigerator Cabinet, of which the following is a specification, reference being had to the accompanying drawings, forming a part hereof.

Fig. 1 is a front elevation of the inside of a refrigerator cabinet embodying my new design, with inside of door in perspective;

Fig. 2 is a side elevation of the cabinet, with inside of open door shown in elevation;

Fig. 3 is a side elevation of the cabinet with door closed;

Fig. 4 is a front elevation of same; and
Fig. 5 is a top plan view of same.

Figs. 3, 4 and 5 are shown on a reduced scale.
The essential features of my design reside in the portions shown in full lines.

I claim:

The ornamental design for a refrigerator cabinet, substantially as shown and described.

MONTGOMERY FERAR.
